ABSTRACT OF THE DISCLOSURE

A method and apparatus for wafering materials such as hay or the like. A rotary drum provided with a plurality of outwardly extending, peripherally spaced projections is advanced intermittently whereby a portion of the material is pushed in one direction by a projection to compress the material. After advancement of the drum one step, a hydraulic ram is pivoted into the path of the material and is advanced in the opposite direction to condense the material into a wafer. The ram is then withdrawn and pivoted out of the path of the projection whereupon the next increment of the step by step advancement of the drum is carried out.

This invention relates to the condensation of compressible materials into relatively small wafers by the application of compressive forces, the primary object being to attain substantial uniformity in density notwithstanding wide differences in the condition of the materials being wafered not only from the standpoint of moisture content but from the standpoint of other inherent characteristics such as its fibrous nature, comminuted state and ability to fuse in response to compressive forces.

It is one of the most important objects of the present invention to provide a system of wafering that is especially adapted for handling hay such as alfalfa and other crops, especially those used for animal feed, utilizing compressive forces in a manner to cause a rather large percentage of the available energy in the initial compaction to the end that a minimum amount of work is required in the final step of application of high compressive forces.

It is another object of my present invention to wafer crops by gathering together the loose material and, at the same time, compress it into a relatively compact mass prior to the final high pressure step with the latter acting upon the precompressed mass continuously until a predetermined pressure is reached, to the end that air is expelled therefrom and fusion takes place with uniform density, rapidity, and minimum energy.

A further important object of the instant invention is to carry out the aforementioned aims through use of novel apparatus capable of withstanding the forces applied to the material by virtue of the way in which precompression takes place in one direction, the precompressed material is shifted along an arcuate path of travel, and the final stage of compression takes place linearly through use of a hydraulic piston and cylinder assembly operating tangentially to the aforementioned path.

In the drawings:

FIGURE 1 is a fragmentary, side elevational view of a wafering machine made pursuant to my present invention and capable of carrying out the novel method hereinafter described;

FIGURE 2 is a fragmentary, elevational view showing the opposite side of the machine;

FIGURE 3 is a substantially central, vertical, cross-sectional view through the machine;

FIGURE 4 is a view similar to FIG. 3 but illustrating certain component parts in a different position;

FIGURE 5 is an enlarged, fragmentary, cross-sectional view taken on line 5—5 of FIGURE 1;

FIGURE 6 is a fragmentary, enlarged, cross-sectional view taken on line 6—6 of FIGURE 1;

FIGURE 7 is an enlarged, fragmentary, cross-sectional view taken on line 7—7 of FIGURE 1;

FIGURE 8 is an enlarged, fragmentary, cross-sectional view taken on line 8—8 of FIGURE 2;

FIGURE 9 is a detailed, cross-sectional view taken on line 9—9 of FIGURE 2; and

FIGURE 10 is a diagrammatical view illustrating the electrical system and components in conjunction with certain of the associated mechanical parts.

The wafering machine of the present invention, broadly designated by the numeral 20, may be stationary or it may be supported on a mobile frame (not shown) which is coupled with a tractor for towing machine 20 through a field. The main body of machine 20 comprises a pair of spaced, parallel, vertical walls 22, each of which includes an upper wall section 24 having an integral, rearward extension 26 and a lower wall section 28 which is connected to the mobile frame by legs 30. Wall extensions 26 are interconnected near the rear of machine 20 by a cross-beam 32, there being a cross member 34 similarly interconnecting upper wall sections 24 near the front of machine 20 (FIG. 3).

Referring to FIG. 2, each upper wall section 24 has a drum support plate 36 mounted thereon, and plates 36 rotatably receive a drum shaft 38 which carries a rotor or drum 40 between and partially within walls 22. Drum 40 is hollow and presents a peripheral rim 41 which travels in closely spaced relationship to upper wall sections 24 as shown in FIG. 6. A plurality of lugs 42 extend outwardly from drum 40 at its periphery, there being five such lugs in the machine illustrated, whereby to present five elongated, circumferential, material-receiving cavities 44a—e. Each lug 42 is split to present a pair of side-by-side advancing anvil faces 46 and corresponding rear faces 47 which define a slot 48 therebetween. Each rear face 47 is backed by a pair of spaced braces 50 secured to rim 41 of drum 40 and presenting a backup receiving recess 51 therebetween.

An arcuate plate 52 spans the distance between walls 22 and is secured to the latter adjacent the instantaneous lower front quadrant of drum 40. Plate 52 is concentric with the drum about shaft 38 and is spaced from drum 40 so that lugs 42 travel in close relationship to the proximal surface of plate 52 (FIG. 6). A knife 54, having a stepped cutting edge 56, is welded to arcuate plate 52 and extends longitudinally thereof in alignment with slots 48 of lugs 42. Knife 54 is in end-to-end relationship with a divider 58 welded to arcuate plate 52 and extending over the latter to present a ram guide 60.

A pair of rectangular backup elements 62 extend through slits in plate 52 and are pivotally mounted on the backup shaft 64 which is secured between walls 22 and disposed between the upper and lower rails 66 of cross member 34. With reference to FIG. 5, backup elements 62 are held in spaced relationship by links 68 and maintained in alignment with slots 51 of lugs 42 by spacers 70 secured between rails 66 of cross member 34. One of the backup elements 62 has a forwardly extending arm 71, the outermost end thereof being interconnected by a tension spring 72 to the outer end of a plate 74 extending forwardly from lower wall section 28. Spring 72 yieldably biases backup elements 62 against rim 41 of drum 40, the upper rear corners of backup elements 62 being bevelled to present complementary drum engaging surfaces 76.

A supply hopper 78 is mounted adjacent drum 40 to communicate with proximal cavities 44 and includes a pair of side walls 80 extending above and coplanar with corresponding upper wall sections 26. A rear plate 82 spans the distance between side walls 80 and presents

an opening 84 therebelow to permit travel of lugs 42 by hopper 78. The forward portions of side walls 80 are interconnected by a front plate 86, the latter defining an opening 87 therebelow which permits swingable travel of a generally triangular feeder 88.

Feeder 88 is pivotally mounted between side walls 80 by a pivot pin 90 which swingably receives the arcuate gate member 92 of feeder 88. An arcuate shelf 94 extends generally forwardly of gate member 92 and swings in an arc directly beneath scraper edge 96 presented by front plate 86. A bracket 98 is secured to gate member 92 adjacent pivot pin 90 and is interconnected with shelf 94 by a brace 100. Hopper 78 and feeder 88 cooperate to form a material-loading station for cavities 44.

Four horizontal shafts are rotatably supported between lower wall sections 28 and include, beginning at the front of the machine, a feeder shaft 102, a cam shaft 104, a planetary shaft 106, and a clutch shaft 108. Referring to FIG. 2, which shows one side of wafering machine 20, clutch shaft 108 has a clutch sprocket 110 rotatable thereon, the sprocket being rotated by acting in cooperation with shaft 108 through a clutch assembly 112. An outer sprocket 114 is secured to planetary shaft 106 for rotation therewith and is interconnected with clutch sprocket 110 by a chain 116, the latter also being trained under an idler sprocket 118. A hydraulic cam wheel 120 and a brake cam wheel 122 spaced inwardly thereof are coupled for rotation with cam shaft 104, as shown in FIG. 9. Cam wheels 120 and 122 are provided with corresponding camming ridges 124 and 126 which will be explained in detail below.

Next, referring to FIG. 1 which shows the other side of wafering machine 20, clutch shaft 108 has a drive wheel 128 rigidly secured thereto, the latter being connected by a drive belt 130 for rotation by a power wheel 132 of a prime mover (not shown) mounted on the mobile frame carrying machine 20. Planetary shaft 106 is rotatably journaled into a bearing mount 134 which is secured on the top surface of platform 136, there being a drive sprocket 138 spaced inwardly of bearing mount 134 on planetary shaft 106 (FIG. 7) and coupled by chain 139 to drum sprocket 141 for driving the drum.

Cam shaft 104 is provided with a cam sprocket 140 rotatable therewith, while feeder shaft 102 is provided with a rigidly secured reducing sprocket 142, the latter being coupled to cam sprocket 140 by a chain 144. The radius of reducing sprocket 142 is one-fourth that of cam sprocket 140, whereby four 360° revolutions of reducing sprocket 142 are required for one full turn of cam sprocket 140.

The portion of the driving structure between walls 22 is shown in FIGS. 3 and 4, there being a feeder sprocket 146 mounted for rotation with feeder shaft 102 and a planetary gear assembly 148 mounted for operation on planetary shaft 106. A connecting arm 150 is rigidly secured to feeder shaft 102 adjacent feeder sprocket 146 and is pivotally coupled at the outer end thereof to a feeder crank 152 which extends upwardly for pivotal connection to bracket 98 of feeder 88. Thus, rotation of feeder sprocket 146 causes reciprocation of feeder crank 152, whereupon feeder 88 pivots about pin 90 toward and away from drum 40, the throw of connecting arm 150 being set to limit inward swinging of the gate member 92; thereby the latter closes the proximal cavity 44 as shown in FIG. 4.

The planetary gear assembly 148, shown in detail in FIG. 7, includes a sun gear 154 keyed for rotation with planetary shaft 106. A pair of planetary gears 156 are meshed with sun gear 154 and are interconnected by a pair of opposed arms 158 which are journaled over planetary shaft 106 and have sleeves 160 extending along the shaft, one of the sleeves rigidly mounting drive sprocket 138. An outer case 162 having a toothed inner surface 164 meshing with planetary gears 156 circumscribes the latter and has a pair of opposed side discs 166 rotatably mounted about sleeves 160 by collars 168.

One of the collars 168 is provided with a feeder driving sprocket 170 which rotates therewith and is coupled to feeder sprocket 146 by a chain 172 (FIGS. 3 and 4). Sleeves 160 and collars 168 are thus freely rotatable with respect to each other and also with respect to planetary shaft 106.

With reference to FIGS. 3 and 4, a brake cylinder 174, having a push rod 176, is secured to one of the legs 30 by a strap 178, push rod 176 being secured to a depending bar 180. A brake arm 182 is rigidly secured to the uppermost end of bar 180 and pivotally carries, at its opposed ends, a pair of brake links 184 which are pivotally mounted between walls 22 by corresponding pin-pins 186. Each link 184 has a brake shoe 188 thereon

in spaced, partially circumscribing relationship to the outer surface of case 162. A coil spring 190 interconnects strap 180 to normally bias push rod 176 into brake cylinder 174 whereby brake shoes 188 do not contact outer case 162.

As shown in FIGS. 2 and 8, a lever 192 is pivotally mounted by a lever shaft 193 for swinging movement parallel to walls 22 and is normally biased upwardly by a coil spring 194 interconnecting the corresponding upper wall section 24 and bracket 196 depending from lever 192. A vertical guide 198 extends laterally from upper wall section 24 and has a longitudinal slot 200 formed therein for receiving lever 192. A latch 202 is pivotally mounted in side-by-side relationship to guide 198, the latch having a notch 204 formed therein for receiving lever 192.

A piston and cylinder assembly structure, broadly designated 206, is pivotally mounted on a flange 208 extending forwardly from crossbeam 32. The cylinder 210 of the structure receives a linearly reciprocable plunger 212, the latter having a forwardly extending ram 214 which terminates in a head 216. As is apparent from FIG. 5, ram 214 and head 216 are vertically split for travel on the opposed sides of ram guide 60 and divider 58. A ram crank 218 underlies plunger 212 and is rigidly secured to lever shaft 193 for swinging movement toward and away from ram 214, there being an upstanding finger 220 on crank 218 for engaging the ram.

Timing mechanism for machine 20 is shown schematically in FIG. 10, with the various parts being arranged corresponding to their positions on machine 20 as illustrated in FIG. 2. The mechanism includes a drum cam 222 having a plurality of laterally extending trip pins 224 and mounted for rotation with drum shaft 38 adjacent support plate 36 (FIG. 2). A latch switch 226 and a solenoid switch 228 disposed in advance thereof, are mounted on drum support plate 36 for actuation by trip pins 224. Latch switch 226 is connected to a latch solenoid 230 having an armature 232 pivotally connected at the uppermost end of lever latch 202 as best shown in FIG. 8.

Solenoid switch 228 has a pair of poles A and B connected through corresponding leads 234 and 236 to a lever switch 238 and a relay control 240. Relay control 240 is connected through line 244 to a relay unit 246 having a relay switch 248 with poles C and D. Lever switch 138, relay control 240, relay unit 246, and relay switch 248 are mounted together in a switching box 250 on an upper wall section 24 underlying lever 192. Actuation of lever switch 238 and relay control 240 is effected by movement of a trip 253 pivotally coupled to switching box 250 and engaging the lower surface of bracket 196. Trip 253 is yieldably biased upwardly whereby the same travels upwardly and downwardly in response to corresponding movements of lever 192.

Pole D of relay switch 248 is connected through lines 252 and 254 to a first valve solenoid 256, the energization of which causes the application of hydraulic pressure through a valve assembly 257 to move plunger 212 outwardly of cylinder 210. Pole C of relay switch 248 is connected through lead 258 to a hydraulic cam switch

260 which is mounted on a bracket 262 underlying hydraulic cam wheel 120 (FIG. 9). Switch 260 includes poles E and F which are alternately connected to lead 258 by the operation of camming ridges 124 of hydraulic cam wheel 120.

Pole A of hydraulic cam switch 260 is connected through lead 264 to line 254 and thereby first valve solenoid 256. Pole B is connected to a second valve solenoid 266 through line 268, the energization of the second solenoid operating through valve assembly 257 to cause retraction of plunger 212 into cylinder 210.

Pole A of solenoid switch 228, in addition to being connected to lever switch 238, is also connected through lead 234 to line 270 and thence to a brake switch 272. Brake switch 272 is mounted on bracket 262 adjacent brake cam wheel 122 (FIG. 9) and the closing of switch 272 is controlled by camming ridge 126. Closing of brake switch 272 causes energization of brake solenoid 274 which, through valve mechanism 276, causes fluid operation of brake cylinder 174 to force push rod 176 outwardly and thereby shift brake shoes 188 into engagement with outer case 162 of planetary gear assembly 148. Switches 226, 228, 238 and 248 are connected to a power source, such as a battery, 278 through corresponding lines.

In operation, hay or other compressible material is continuously fed from a conveyor belt 280 into supply hopper 78 for precompression in cavity 44a as shown in FIG. 3. During precompression, rotation of power wheel 132 of the prime mover causes corresponding rotation of drive wheel 128 and clutch shaft 108 which, in turn, through actuation of clutch assembly 112, causes rotation of clutch sprocket 110 for driving outer sprocket 114. Rotation of outer sprocket 114, acting through planetary shaft 106, causes rotation of sun gear 154, whereupon planetary gears 156 remain stationary with respect to planetary shaft 106 due to the resistance against rotation of drum 40 caused by the hay being fed into the loading station. Planetary gears 156 thus must rotate about their respective axes which cause rotation of outer case 162 and consequently feeder driving sprocket 170 rotates.

Rotation of feeder driving sprocket 170 causes corresponding rotation of feeder sprocket 146 which revolves connecting arm 150 to vertically reciprocate feeder crank 152 and swing gate member 92 toward and away from drum 40 to press the hay against the latter radially thereof. When gate members 92 is swung to a closed position over drum 40, as shown in FIG. 4, hay will be received on shelf 94, whereupon, when gate member 92 swings away from drum 40, the hay upon shelf 94 is wiped off by scraper edge 96 and falls into cavity 44a for subsequent packing.

While feeder 88 is filling, shafts 102, 104, 106 and 108 all rotate to revolve the corresponding sprockets and cam wheels. The electrical switching positions are set subsequently as shown in FIG. 10 with solenoid switch 228 at the B pole; latch switch 226 opens whereby solenoid 230 is de-energized so that armature 232 will be extended to push latch 202 into holding position with notch 204 embracing lever 192 to hold the latter in its lower position; lever switch 238 closed; relay switch 248 at the C pole; cam switch 260 at the E pole; brake switch 272 open with brake solenoid 274 thereby being de-energized; relay control 240 open and thereby relay 246 de-energized; first valve solenoid 256 energized for forcing plunger 212 outwardly for compression of the hay in cavity 44c which was filled in a preceding cycle; and second valve solenoid 266 de-energized.

Feeder sprocket 146, through feeder shaft 102, rotates reducing sprocket 142 whereby chain 144 drives cam sprocket 140 to rotate cam wheels 120 and 122 through cam shaft 104. The 4:1 radius ratio of cam sprocket 140 and reducing sprocket 142 results in four revolutions of feeder sprocket 146 for each full turn of cam wheels

120 and 122. One full turn of cam wheels 120 and 122 represents a cycle of operation of machine 20, and thus feeder 88 swings toward and away from drum 40 four times for each cycle. Prior to the fourth reciprocation of gate member 92, camming ridge 124 of hydraulic cam wheel 120 shifts the contact arm of cam switch 260 from pole E to pole F to simultaneously energize second valve solenoid 256, de-energizing first valve solenoid 266. Valve assembly 257 is thereby operated to retract ram 214 from cavity 44c to the position shown in FIG. 4.

10 The operation of the stepping mechanism for drum 40 proceeds in the following manner. Upon completion of the fourth reciprocation of gate member 92, brake cam wheel 122 will have advanced to a position whereby camming ridge 126 closes switch 272 which, through line 270 and switch 238, receives current from battery 278 to energize solenoid 274 and thereby cause fluid operation of brake cylinder 174 to advance push rod 176 to pivot brake shoes 188 into engagement with the outer surface of case 162 to stop rotation of the latter. When case 162 stops, there is also discontinuance of rotation of feeding shaft 102, cam shaft 104 and the wheels and cams thereof. Since sun gear 154 continues to rotate, and the resistance of brake shoes 188 is greater than the resistance against rotation of drum 40, planetary gears 156 rotate about their axes in meshing cooperation with toothed surface 164 of case 162 and are thereby caused to revolve about planetary shaft 106 to rotate sleeves 160 to commence counterclockwise rotation (FIGS. 1, 15 20 25 30 35 40 45 linear travel of ram 214 into and along cavity 44b, longitudinally of the latter and tangentially of the drum, toward anvil faces 46 of lug 42. A toroidal compression station is defined by side walls 22, arcuate plate 52 and rim 41 of drum 40 and assembly 206 and lugs 42 comprise condensing structure for compacting the material at said station.

When the contact arm of switch 228 is thrown to begin compression by piston and cylinder assembly 206, there is a corresponding de-energization of brake solenoid 274 since current thereto was carried through pole A of switch 228. De-energization of brake solenoid 274 operates valve mechanism 276 to permit spring 190 to retract push rod 176 to thereby shift brake shoes 188 outwardly from case 162 whereby the latter commences to rotate to start a new cycle of filling by feeder 88.

When the filling operation begins, a laterally extending roller 286 on feeder crank 152 engages the upper surface of lever 192 upon the first downward reciprocation of the crank to shift lever 192 within lever notch 204 and thereby, effects relatching of lever 192. The downward swinging of lever 192 closes switch 238 and opens relay control 240 but cam wheel 120 reshifts switch 260 to pole E to sustain energization of first valve solenoid 256. Swinging of lever 192 causes a corresponding lowering of ram crank 218, but ram 214 is within the compression chamber and, therefore, will not drop down.

While feeder 88 is filling cavity 44e which has advanced to the loading station, ram 214 is being forced against the units within cavity 44b until a preset pressure is reached, at which time ram 214 dwells against the units. Compression within the compressing station is substantially perpendicular to the packing force of feeder 88 whereby maximum density is obtained to form the final hay wafers 284. The linear force of ram 214 is borne primarily by backup elements 62 as they engage rear faces 47 of lug 42. This protects against breaking or weakening of the lugs. Ram 214 is then retracted as explained before, when the camming ridge 124 of hydraulic cam wheel 120 has rotated to a proper position to cause movement of the contact arm of switch 260. Switch 260 is shifted to the B pole to de-energize first valve solenoid 256 and simultaneously energize second valve solenoid 266 which effects retraction of ram 214, the latter dropping down to finger 220 which was previously lowered.

Thus, as outer case 162 rotates, there will be simultaneous action of feeder 88 and ram 214 in corresponding cavities 44, with drum 40 remaining stationary. When outer case 162 is engaged by brake shoes 188, feeder 88 discontinues reciprocation while simultaneously drum 40 begins to rotate. The drive assembly for the machine therefore, operates as a stepping mechanism to advance the cavities successively past the loading, cutting and compressing stations. During rotation of drum 40 there is no reciprocation of ram 214, although the latter is raised at a predetermined time to begin compression of the advancing sliced units. Advance of ram 214 begins only when drum 40 stops rotating, thus permitting insertion of a backup means to protect against high pressures being placed directly on the lugs, whereby the latter will not become weakened over a prolonged period of use, and also to hold drum 40 against retrograde rotation during compression of the units.

The valve system for piston and cylinder assembly 206 is arranged to deliver a continuous pressure to plunger 212 for a predetermined period of time during each dwell in the rotations of drum 40, whereby the density of the wafers formed in the compressing station is substantially uniform even if hay is delivered at a nonuniform rate to hopper 78. Thus, whether a large or small amount of hay is received by a cavity 44, the same pressure will be impressed thereon in the compression station with the final wafers varying in size corresponding to the original hay packed by feeder 88.

The sequential steps performed on a particular wafer 284 by machine 20 thus may be summarized as follows: hay or other compressible material is gathered into an elongated mass in cavity 44a at the loading station and packed by a compressive force applied by feeder 88 radially (substantially transversely) of the mass, with the gathering and packing being simultaneous and intermittent as feeder crank 152 reciprocates to add hay following each application of packing force; after packing, the mass in cavity 44a is pushed at one end thereof by a lug 42 along an arcuate path of travel about drum 40 into a cutting station where the mass is severed longitudinally into a pair of side-by-side units; the mass then continues on its arcuate path into a compressing station or zone where it is held against longitudinal movement by backup elements 62, against lateral movement by walls 22, and against radial movement by rim 41 and plate 52; after the mass comes to rest in the zone, ram 214 applies a longitudinal compressive force on the other end of the mass in a lineal direction tangential to the arcuate path of the mass, the mass being condensed into a wafer by achieving a predetermined pressure and by application of longitudinal pressure to the wafer for a preset period of time, whereupon the ram is retracted to release the longitudinal compressive force.

The rotary action, of course, provides continuous operation as the hay is gathered into successive, elongated masses in cavities 44a-44e. The cavities successively communicate with hopper 78, and while one cavity is being packed by feeder 88, the hay in the next preceding cavity is subdivided by knife 54 and the units are being compressed in yet a third cavity, the latter being backed up by elements 62 in the next preceding cavity.

Many adjustments may be made in machine 20 to adapt it for hay or other material with varying moisture and fiber content, state of comminution, and fusing characteristics. For example, the 4:1 ratio between cam sprocket 140 and reducer sprocket 142 may be changed to vary the number of filling reciprocations of feeder 88 for each cavity. The time of dwell may be varied on the application of force by ram 214 by altering the camming ridges on the cam wheels. In this regard, the ridges may be formed of a plurality of side-by-side removable units which can be selectively removed or added to vary the arc length of the ridge and thereby vary the time period of pressure application. It should also be noted that better results have been obtained with chopped hay serving as the original feed.

It will be appreciated that a field machine would probably have a drum with a wider rim so that a row of lugs 42 may be provided to form a plurality of wafers simultaneously. Each lug 42 would have a corresponding split ram 214 to effect the compression operation.

Having thus described the invention, what is claimed as new and desired to be secured by Letters Patent is:

1. A wafering machine comprising:
a rotor having lug means at its periphery, presenting an elongated cavity extending circumferentially of the rotor;
a material loading station adjacent said periphery;
a material compressing station adjacent said periphery in advance of the loading station with respect to the direction of rotation of the rotor;
stepping mechanism coupled with the rotor for rotating the latter step by step to advance the cavity successively past said stations;
a feeder at said loading station for filling the cavity with said materials; and
structure at said compressing station, movable between each step of rotative advancement of the rotor, into and along the cavity, longitudinally of the latter and tangentially of the rotor, for condensing the material against said lug means.
2. The invention of claim 1; and
a backup for said lug means movable to a position

- therebehind immediately prior to each operation of said structure.
3. The invention of claim 1, said feeder having means for packing the material into the cavity. 5
4. The invention of claim 1, there being means interconnecting said mechanism and the rotor for holding the latter against rotation during filling of the cavity with material by said feeder. 10
5. The invention of claim 1, there being a plurality of lug means, presenting a number of cavities whereby, during each operation of said structure within a cavity, said feeder operates to fill another of the cavities. 15
6. The invention of claim 5, and a backup for said lug means movable to a position therebehind into still another of said cavities immediately prior to each operation of said structure. 20
7. The invention of claim 1, said structure including a reciprocable ram having means for exerting a steady pressure on the material for a predetermined period of time during each dwell in the rotation of the rotor. 25
8. The invention of claim 7, said structure having means for reciprocating the ram along a substantially linear path of travel. 30
9. The invention of claim 1, and a knife means within the path of travel of the material in the cavity from the loading station to the compressing station for subdividing the material into a number of separate units. 35
10. The invention of claim 3, said feeder including a member movable toward and away from the rotor to press the material against the latter radially thereof. 40
11. The invention of claim 10, and a material supply hopper communicating with the cavity when the latter is adjacent the loading station, said member operating within the hopper. 45
12. A wafer machine comprising: a rotor having a plurality of outwardly extending lugs, presenting a number of elongated, circumferential, material-receiving cavities; a material supply hopper disposed for successive communication with the cavities during rotation of the rotor; 50 a feeder swingable within the hopper toward and away from the rotor for packing the material into the cavities radially of the rotor when the cavities are in communication with the hopper; a knife means in advance of the feeder within the path of travel of the material in the cavities for subdividing the material into a number of separate units; a fluid piston and cylinder assembly, in advance of said knife means, having a reciprocable ram movable into the path of travel of said units for compressing the latter; 55 stepping mechanism coupled with said rotor for intermittent rotative advancement of the latter whereby, during each dwell in rotor advancement, material is packed into one cavity, the material is subdivided in the next preceding cavity and units are compressed in a third cavity; a lug backup element movable into said next preceding cavity during each of said dwells for holding the rotor against retrograde rotation during compression of the units by the ram; and 60
- 65

- means coupled with said assembly for shifting the ram into said third cavity prior to each compressing movement of the ram longitudinally of the third cavity, tangentially of the rotor, and toward the lug being backed up by said element.
13. The method of wafering a compressible material comprising: gathering the material together into an elongated mass; applying a compressive force on the mass transversely thereof; pushing on one end of the transversely compressed mass to shift the same into a zone for further handling; holding the elongated mass against lateral movement while in said zone; holding said mass at said one end of the latter against longitudinal movement of the mass from within said zone; applying a compressive force on said transversely compressed mass at the opposite end thereof toward said one end by a moving member to initially compress said mass while it is being shifted to said zone to condense the mass longitudinally thereof; and continuing the application of said longitudinal force on said mass until a predetermined pressure has been exerted thereon.
14. The invention of claim 13: and releasing said longitudinal compressive force from said mass after the latter has been held for a period of time at said predetermined pressure.
15. The invention of claim 13; and severing the elongated, transversely compressed mass longitudinally thereof into a plurality of side-by-side units prior to the application of said longitudinal force.
16. The invention of claim 15, and severing into said units while the transversely compressed mass is being shifted to said zone.
17. The invention of claim 13, said gathering of the material and said application of transverse forces being simultaneous and intermittent whereby additional material is added following each application of the transverse force.
18. The invention of claim 13, and gathering the material together into successive elongated masses and applying transverse compressive force thereto during longitudinal compression of each preceding, transversely compressed mass.
19. The invention of claim 13, said pushing being along an arcuate path of travel, said application of longitudinal compressive force being lineal and tangential to said path.
20. The invention of claim 19, and holding the mass during pushing against lateral movement and against movement radially of said path.
